UNITED STATES PATENT OFFICE.

CHARLES C. ABBOTT, OF PITTSFIELD, MASSACHUSETTS, ASSIGNOR TO GENERAL ELECTRIC COMPANY, A CORPORATION OF NEW YORK.

ELECTRIC HEATING UNIT.

1,393,732.

Specification of Letters Patent. Patented Oct. 18, 1921.

Application filed December 17, 1920. Serial No. 431,467.

To all whom it may concern:

Be it known that I, CHARLES C. ABBOTT, a citizen of the United States, residing at Pittsfield, county of Berkshire, State of 5 Massachusetts, have invented certain new and useful Improvements in Electric Heating Units, of which the following is a specification.

My invention relates to electric heating 10 units and has for its object the provision of simple, compact and reliable means for generating heat by the use of an electric current.

More specifically my invention relates to 15 an electric heating unit of the resistance type. It is often advantageous in the heating of various types of machinery to use a small compact heating unit which is designed to operate on a low voltage grounded 20 circuit. My invention is particularly adapted for use in installations of this character, although it has other applications.

Other objects and features of my invention will appear in the course of the following 25 specification in which I have shown my invention embodied in concrete form for the purpose of illustration.

Referring to the drawing, Figure 1 shows 30 a perspective view of a heating unit constructed in accordance with my invention; Fig. 2 is a vertical enlarged section of the device shown in Fig. 1, while Fig. 3 is a plan view showing various parts in dotted lines.

Referring to Fig. 2 of the drawing, a cylindrically shaped insulator or core 12, constructed of lava or other suitable material, is supported in a central position in casing 10 by means of a stud 14 which co-operates 35 with a hole in the insulator. Stud 14 is rigidly fixed to the casing in any suitable manner.

The insulator 12 has a peripheral groove 26 in which a helical resistance element 13 is supported. One end of the resistance element extends through the casing at point 21 where it is brazed to the casing in a slot 27, making a "ground" connection. The other end of the resistance element is brazed in a 40 slot 22 in the end of terminal post 18. Terminal post 18 is securely anchored in the casing by means of a metallic disk 15 having a threaded hole into which the terminal post is screwed by means of co-operating threads 45 on the end thereof and securely brazed. The

terminal post extends a short distance through disk 15, to provide for which the insulator 12 is cut away as shown at 25. Disk 15 is insulated from stud 14 by washer 17 made of a suitable insulating material 50 and from casing 10 by insulating washer 16. Insulating washer 20 is seated in a depression 20' in the casing and holds the terminal post in central position in hole 19 in the casing through which the terminal post extends. The terminal post is thereby insulated from the casing. A suitable connecting terminal 24 is attached at the outer end 55 of the terminal post.

After the various parts mentioned above 60 have been assembled, as shown in the drawing, the casing is filled with a granular insulating material 23, such as magnesium 65 oxid. The casing is then vibrated to shake the insulating material together after which 70 the cover 11, consisting of a metallic disk having a sloping edge, is put in place and the unit subjected to heavy pressure whereby it is compressed to a solid compact mass. The upper edge of the casing is then compressed to a slightly smaller diameter onto 75 the sloping edge of the top 11 thus firmly sealing the top in place.

In a heating unit which is constructed as 80 previously described the granular insulating material will be packed within the casing around the insulator, and around the 85 resistance element between the turns thereof.

While I have here shown an embodiment 90 of my invention which is, at present, the best means known to me, I would have it 95 understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is,—

1. An electric heating unit comprising a 100 casing, a core of insulating material in said casing having a groove, a resistance element wound in helical form and wound in said groove, and granular insulating material packed within the casing around the 105 core and the resistance element.

2. An electric heating unit comprising a 110 casing, a core of insulating material in said casing having a groove, a helical resistance element supported on said core with its axis

in said groove, and granular insulating material packed within the casing around the core and the resistance element.

3. An electric heating unit comprising a metallic casing, a cylindric core of insulating material in said casing having a peripheral groove, a helical resistance element supported on said core with its axis in said groove, and granular insulating material packed within said casing around the core and the resistance element.

4. An electric heating unit comprising a metallic casing, a core of insulating material in said casing having a groove, a helical resistance element supported on said core with its axis in said groove having one end connected to the casing, a terminal insulated from the casing for the other end of the resistance element, and granular insulating material packed within the casing around the core and the resistance element.

5. An electric heating unit comprising a metallic casing, a core of insulating material in said casing having a groove, a helical resistance element supported on said core with its axis in said groove having one end connected to the casing, a terminal supported within the casing and insulated therefrom for the other end of said resistance element, and granular insulating material packed within the casing around the core and the resistance element.

6. An electric heating unit comprising a metallic casing, a core of insulating material supported in said casing and having a groove, a helical resistance element on said core with its axis in said groove having one

end connected to the casing, a terminal extending without the casing for the other end of the resistance element, a metallic disk in the casing for supporting the terminal, means for insulating said disk and terminal from the casing, and granular insulating material packed within the casing around the core and the resistance element.

7. An electric heating unit comprising a metallic casing of heat conducting material, a cylindric insulator having a peripheral groove in said casing, a helical resistance element supported on said insulator with its axis in said groove having one end connected to the casing, a terminal insulated from the casing for the other end of the resistance element, and granular insulating material packed within the casing around the insulator and the resistance element.

8. An electric heating unit comprising a metallic casing of heat conducting material, a cylindric insulator having a peripheral groove supported centrally in said casing, a helical resistance element supported on said insulator with its axis in said groove having one end connected to the casing, a terminal extending without the casing for the other end of the resistance element, a metallic disk in the casing for supporting said terminal, means for insulating the disk and terminal from the casing, and granular insulating material packed within the casing around the insulator and resistance element.

In witness whereof, I have hereunto set my hand this 13th day of December, 1920.

CHARLES C. ABBOTT.
